TIME-DELAY RELAY SYSTEM

Robert M. Lommen, Lombard, Ill., assignor to
Cutler-Hammer, Inc., Milwaukee, Wis., a corporation of Delaware

Continuation of application Serial No. 629,051,
November 16, 1945. This application February
15, 1951, Serial No. 311,116

8 Claims. (Cl. 175—320)

1

The invention relates to timing systems and while not limited thereto is especially adapted for the timing of current supply to a welding transformer.

This application is a continuation of my application Serial No. 629,051, filed November 16, 1945, now abandoned.

An object of the invention is to provide a timing system which upon initiation of the flow of current in a translating circuit will maintain said flow for an adjustable period.

Another object is to provide a system which will supply, upon the operation of an initiating pilot device, a single current impulse of pre-adjustable duration.

Another object is to provide means for controlling the duration of a current impulse supplied to a translating circuit, and limiting such duration to a given preselected maximum interval.

Other objects and advantages will hereinafter appear.

The accompanying diagrammatic drawing is illustrative of an embodiment of the invention.

In the drawing,

Figure 1 is a diagram of connections for controlling welding impulses of given duration, while

Fig. 2 is a modification of Fig. 1, in which the duration of the welding impulses may be shortened at will.

Referring to Fig. 1, L¹, L² represent the bus bars of an alternating current supply system. Connected to the line L¹ is one terminal of the primary winding 10^a of a welding transformer 10 which also has a secondary winding 10^b supplying current to a pair of welding electrodes 11. A second terminal of the primary winding 10^a is connected through the normally open contacts 12^b of an electromagnetic switch 12 to the line L². The electromagnetic switch 12 is provided with an energizing winding 12^a. To initiate the power supply to the transformer 10, the system is provided with a normally open contact push button switch 13, one terminal of which is connected to the line L¹. A second terminal of the push button switch 13 is connected to one terminal of a normally closed contact 14^b of an electromagnetic relay 14 which is provided with an energizing winding 14^a. A second terminal of the contact 14^b is connected to one terminal of the winding 12^a and the second terminal of the winding 12^b is connected to the line L². Connected in parallel with the contacts 13 are the normally open contacts 15^b of an electromagnetic relay 15 which is provided with an energizing winding

2

15^a connected in parallel with the winding 12^a.

There is also connected across the lines L¹, L², but in series with contacts 13, the primary winding 16^a of a transformer 16, said transformer 5 having secondary windings 16^b and 16^c. The winding 16^b is adapted to supply power to a gaseous electron tube 17. The tube 17 has a cathode 17^a, an anode 17^b, a control electrode 17^c, and a screen grid electrode 17^d. One terminal of the 10 winding 16^b is connected to the cathode 17^a while the second terminal is connected through the winding 14^a to the anode 17^b. The cathode 17^a is also connected to the screen grid electrode 17^d. A condenser 18 is connected in shunt with 15 the winding 14^a. The control electrode 17^c is connected through a resistor 19 in series with a condenser 20 to one terminal of the secondary winding 21^b of a transformer 21. The other terminal of the winding 21^b is connected to one terminal 20 of the winding 16^c, while the other terminal of the winding 16^c is connected to the cathode 17^a. The transformer 21 has a primary winding 21^a connected across the lines L¹ and L². The condenser 20 is paralleled by an adjustable resistor 22 connected in series with a fixed resistor 23.

The system operates in the following manner: When the lines L¹ and L² are energized, the primary winding 21^a is energized and the voltage of 30 the winding 21^b is impressed between the cathode 17^a and the control electrode 17^c to charge the condenser 20. Due to the rectifying action of tube 17 the charge is such that it renders the control electrode 17^c negative with respect to the 35 cathode 17^a. When the push button switch 13 is depressed, the relay coils 15^a and 12^a are energized and current is supplied to transformer 10 while the relay 15 provides a maintaining circuit around the push button 13. The transformer 40 winding 16^a is also energized. This impresses a voltage between the cathode 17^a and anode 17^b, but the tube remains non-conducting by virtue of the negative potential of the control electrode 17^c. A potential is also induced in winding 16^c 45 which is slightly higher than and opposed to the potential induced in the winding 21^b; so that the potential which is impressed upon the condenser 20 is reduced to a very small alternating ripple voltage which causes the unidirectional charge 50 of the condenser to slowly decay through the resistors 22 and 23.

When the voltage of the grid 17^c reaches the critical or firing voltage, conduction through the tube 17 starts. The point of starting is more accurate by virtue of the alternating ripple voltage

aforementioned. This energizes the relay winding 14^a and the relay 14 opens the contacts 14^b which in turn deenergizes relay 12 and interrupts the welding current. As stated, energization of winding 15^a closes the contacts 15^b, which establishes a maintaining circuit in parallel with the push button 13 so that the push button 13 may be released without interrupting the energizing connections of the windings 12^a and 15^a, and current will continue to be supplied to the transformer winding 16^a. Opening of contact 14^b deenergizes relay 15, thus opening the maintaining circuit for push button 13, so that if the latter is released relay 14 will be deenergized and restored to its normal position, thereby again closing the contact 14^b. Thereupon the system is in its initial condition for a second operation.

Referring now to Fig. 2, it will be observed that the relay 15 with its contact 15^b is omitted. In this case the circuit of relay 12 is interrupted upon release of the push button 13, but if the push button 13 is held closed beyond the period of conduction of tube 17, that is, until after the relay 14 has responded, the welding current will not be reestablished until the push button switch 13 is released to return the relay 14 to its normal position and then the push button is depressed again. Thus, in either case, the maximum time during which the welding current can flow upon each depression of the push button 13 is limited.

The condenser 19 is for the purpose of smoothing out the half wave rectified current supplied to the winding 14^a. By adjusting the resistor 22 and/or the condenser 20 it is possible to adjust the time of operation within wide limits.

The gaseous tube 17 shown may be replaced by a suitable high vacuum tube and the screen grid 17^a may be omitted in either case without departure from the essence of the present invention. Other modifications within the scope of the invention will be apparent to those skilled in the art.

I claim:

1. In combination, an electric supply circuit, means to be supplied with a current impulse derived from said supply circuit, an electron tube having an auxiliary electrode for control, a condenser in circuit with said auxiliary electrode and the cathode of said tube and having a regulable discharge path, continuously acting means for subjecting said condenser to a charge by power derived from said supply circuit which condenser charge energizes said auxiliary electrode to a degree blocking conduction of said tube, normally inactive means which when energized with electrical power affords neutralization of the condenser charging action of said continuously acting means and affords a supply of power through the main conducting path of said tube, means for initiating flow of current from said supply circuit to said first mentioned means and said normally inactive means, and means responsive to power conduction of said tube for interrupting the flow of current to said first mentioned means.

2. In combination, an electric supply circuit, an electron tube having a cathode, an anode and a control electrode, a condenser in circuit with said cathode and said control electrode, a regulable discharge path connected across said condenser, a transformer having its primary winding connected to said supply circuit and having a secondary winding in circuit with said condenser to charge the same by power derived from said supply circuit and subject said electrode to a potential blocking conduction of said tube, nor-

mally inactive means which when energized with electrical power affords neutralization of the condenser charging effect of said transformer and affords a supply of power through the main conducting path of said tube, a translating device, means for initiating flow of current from said supply circuit to said translating device and said normally inactive means, and means responsive to power conduction of said tube for interrupting the flow of current to said translating device.

3. In combination, an electric supply circuit, an electron tube having a cathode, an anode and a control electrode, a condenser in circuit with said cathode and said control electrode, a regulable discharge path connected across said condenser, a first transformer having its primary winding connected to said supply circuit and having a secondary winding in circuit with said condenser to charge the same by power derived from said supply circuit and subject said electrode to a potential blocking conduction of said tube, a second transformer having a primary winding and secondary winding means in circuit with the secondary winding of said first transformer and the main conducting path of said tube for neutralizing the charging action of said first transformer and affording a source of power through the main conducting path of said tube upon energization of the primary winding, a translating device, means to initiate current flow from said supply circuit to the primary winding of said second transformer and to said translating device, and means responsive to power conduction of said tube for interrupting the flow of current to said translating device.

4. In combination, an electric supply circuit, an electron tube having a cathode, an anode and a control electrode, a condenser, a regulable discharge path connected across said condenser, a first transformer having its primary winding connected to said supply circuit and having a secondary winding in circuit with said cathode, said control electrode and said condenser to charge the latter and subject said control electrode to a potential which renders said tube non-conducting, a second transformer having a primary winding and two secondary windings, one of said secondary windings being in circuit with the secondary winding of said first transformer and being effective to neutralize the charging effect of said first transformer and the other of said secondary windings being in circuit with the anode and cathode of said tube to afford a source of power through the main discharge path of said tube whenever the primary winding is energized, a translating device, means for initiating current flow from said supply circuit through the primary winding of said second transformer and through said translating device, and means responsive to power conduction of said tube to terminate the flow of current through said translating device.

5. In combination, an electric supply circuit, an electron tube having a cathode, an anode and a control electrode, a condenser, a regulable discharge path connected across said condenser, a first transformer having a primary winding connected across said supply circuit and a secondary winding in circuit with said cathode, said control electrode and said condenser to charge the latter for subjecting said control electrode to a potential blocking conduction of said tube, a second transformer having a primary winding and two secondary windings one of which is in circuit with the secondary winding of said first

transformer and being effective upon energization of the primary winding to neutralize the condenser charging effect of said first transformer, a translating device, electroresponsive means energizable to afford supply of current derived from said supply circuit to said translating device, and means for controlling the energization of said electroresponsive means and the primary winding of said second transformer including a normally open switch operable to energize said electroresponsive means and the primary winding of said second transformer with power from said supply circuit and further including an electromagnetic relay having an energizing winding connected in circuit with the main discharge path of said tube in series with the other secondary winding of said second transformer and being responsive to power conduction of said tube to effect deenergization of said electroresponsive means.

6. In a welding control system, the combination with an electroresponsive switch through the medium of which welding operations are controlled, of a control circuit for said switch comprising an electron tube having an auxiliary electrode for control, a condenser in circuit with said auxiliary electrode and the cathode of said tube and having a regulable discharge path, means to be continuously energized with electrical power to charge said condenser and subject said auxiliary electrode to a potential blocking conduction of said tube, normally inactive means which when energized with electrical power affords neutralization of the condenser charging action of the first mentioned means and affords a supply of power through the main conducting path of said tube, and an energizing circuit for said switch and said normally inactive means including means operable to complete such circuit and further including means responsive to power conduction of said tube to deenergize said switch.

7. In a welding control system, the combination with an electroresponsive switch through the medium of which welding operations are controlled, of a control circuit for said switch comprising an electron tube having an auxiliary electrode for control, a condenser in circuit with said auxiliary electrode and the cathode of said tube and having a regulable discharge path, means to be continuously energized with elec-

trical power to charge said condenser and subject said auxiliary electrode to a potential blocking conduction of said tube, normally inactive means which when energized with electrical power affords neutralization of the condenser charging action of the first mentioned means and affords a supply of power through the main conducting path of said tube, and an energizing circuit for said switch and said normally inactive means including means operable to complete such circuit and further including means responsive to power conduction of said tube to deenergize said switch and said normally inactive means.

15. 8. The combination with a welding transformer and a source of electrical supply, of means energizable to connect the primary winding of said transformer to said source, an electron tube having an auxiliary electrode for control, a condenser in circuit with said auxiliary electrode and the cathode of said tube and having a regulable discharge path, continuously acting means for subjecting said condenser to a charge by power derived from said source which 20 condenser charge energizes said auxiliary electrode to a degree blocking conduction of said tube, normally inactive means which when energized with electrical power affords neutralization of the condenser charging action of said continuously acting means and affords a supply of power 25 through the main conducting path of said tube, means for initiating flow of current from said source to said first mentioned means and said normally inactive means, and means responsive 30 to power conduction of said tube for interrupting the flow of current to said first mentioned means.
